ARTICLE HOLDING TRAY

Wilbur L. Hoff, Hollywood, Ill., assignor to Western Electric Company, Incorporated, New York, N. Y., a corporation of New York

Application August 6, 1943, Serial No. 497,716

10 Claims.

(Cl. 41—9)

This invention relates to article holding trays and more particularly to trays for holding crystals during the etching of them.

It is an object of the present invention to provide a simple, rugged article-holding tray in which articles may be carried during the processing of them.

In accordance with one embodiment of the invention, a box-like structure of hard rubber is provided with removable shelves, which may be locked in the box-like structure with removable pins. These shelves are provided with transverse slots to receive large crystals which may be held on the shelves by removable side plates locked on the box-like structure with removable pins.

In another embodiment of the invention, the removable side plates are eliminated and nesting shelves having suitably shaped apertures are locked by removable pins in an open-ended framework, in position to hold smaller crystals between notched upper edges of the apertures of a lower shelf and the lower surface of an adjoining upper shelf.

A complete understanding of the invention may be had by reference to the following detailed description when considered in conjunction with the accompanying drawings, wherein

Fig. 1 is a plan view of one embodiment of the invention, adapted to hold relatively large crystals, parts being broken away to more clearly illustrate those parts located beneath them;

Fig. 2 is a horizontal view, partly in section, taken substantially along the line 2—2 of Fig. 1 in the direction of the arrows, and showing a portion of the apparatus in side elevation;

Fig. 3 is an irregular vertical sectional view taken substantially along the line 3—3 of Fig. 2 in the direction of the arrows; and

Fig. 4 is an exploded view of the apparatus shown in Figs. 1, 2 and 3 on a reduced scale showing the ends of the main body of the apparatus, the shelves, and the side plates disassembled;

Fig. 5 is a side elevational view of the second embodiment of the apparatus designed to hold relatively small crystals, parts being broken away to show those parts in back of them more clearly;

Fig. 6 is a plan section taken substantially along the line 6—6 of Fig. 5 in the direction of the arrows, some of the parts being broken away to more clearly show those parts beneath them;

Fig. 7 is a transverse vertical sectional view taken substantially along the line 7—7 of Fig. 5 in the direction of the arrows; and

Fig. 8 is a partially exploded view on a smaller scale than Figs. 5, 6 and 7 showing the end eleva-

tion of the main framework of the apparatus and showing the ends of the nesting shelves, some of them in nesting engagement and others of them displaced slightly to illustrate their construction more clearly.

In the embodiment of the invention as illustrated in Figs. 1 to 4, inclusive, there is provided a box-like structure comprising a top plate 11 and a bottom plate 10 rigidly attached to four end members 12, 13, 14 and 15. The end members 12, 13, 14 and 15 have their outer edges in alignment with the front and rear edges of the top and bottom plates and have their adjacent inner edges spaced apart slightly to provide passages 16 and 17 through which bath materials may pass to the interior of the structure to either etch or rinse crystals enclosed in the holder.

Adjacent its right and left ends, the bottom plate 10 is provided with raised portions 18 and 19 (Fig. 2) which serve to support a lower shelf 20. Adjacent the front and rear ends of the raised portions 18 and 19, grooves 21 and 22 (Fig. 3) are formed therein for receiving projecting lugs 23 and 24 extending downwardly from the lower edges of side plates 25 and 26. The side plates 25 and 26 are provided with sockets 27—27 (Figs. 2 and 3), which are adapted to receive pins 28—28, which serve to lock side plates 25 and 26 in the position shown in Fig. 3, the pins 28—28 passing through apertures 29—29 in the top plate 11. In order to properly locate the plates 25 and 26 so that the sockets therein will align with the apertures 29 in the top plate, four pins 30 are fixed to the top plate 11 and extend downwardly a short distance below the surface thereof to engage the inner surfaces of the side plates.

The end plates 12 and 13, each have a pair of grooves 31 and 32 formed therein and extending horizontally, the grooves 31 being formed at a lower level and the grooves 32 at an upper level, but the grooves 31 in both plates 12 and 13 being in alignment, as well as the grooves 32 in both plates 12 and 13. Grooves or ways 33 and 34 are formed in each of the end members 14 and 15 in alignment with the grooves 31 and 32. These grooves or ways are cut into the end plates to receive the ends of shelves 35 and 36, which are of exactly the same construction and each of which has a series of slots 37 cut therein to receive relatively large crystals 38. In addition to having the slots 37 cut in them to receive the crystals 38, the shelves 35 and 36 have a plurality of apertures 39 formed in them which extend through the body of the shelves and into the slots 37, thereby to permit the acid with which the crystals are to be

etched to pass freely to all of the surfaces of the crystals and also to permit the rinsing material to reach all of the surfaces of the crystals.

In order to facilitate the loading of the crystals into the holding tray, the shelves 35 and 36 have notches 40 formed at their ends for receiving retainer pins 41, which may be passed through apertures 42-42 in the top plate 11 and into suitably formed sockets 43 formed in the bottom plate 10. The side plates 25 and 26 are provided with finger holes 44 which facilitate the insertion or removal of the side plates into the position shown in the various figures and also permit the acid into which the crystals are to be dipped to more freely enter the cavity of the holding tray. In addition to this entrance aperture to the interior of the holding tray, the top plate 11 and bottom plate 10 have apertures 45-45 and 46-46, respectively, formed therein to further facilitate the entrance of the etching and rinsing baths to the cavity of the tray. The top plate 11 has a handle 47 attached to it in any suitable manner whereby the tray may be handled during the processing of the crystals therein.

All of the hereinbefore described parts are made of acid resisting material comprising either natural rubber or one of the rubber substitutes which will be acid resistant and this applies to all of the pins, shelves and plates, as well as the handle of the apparatus. It should be noted that either large or small crystals of irregular configuration may be etched and rinsed by placing them in the tray either with or without the shelves 35 and 36 in place in the tray as long as the crystals are too large to fall out through the finger holes 44. When irregularly shaped crystals are being etched and rinsed the side plates 25 and 26 will hold them in place in the tray.

In the embodiment of the invention disclosed in Figs. 5 to 8, inclusive, all of the parts are also made of acid resisting material, preferably hard rubber, and the construction of this form of invention is slightly different from that described hereinbefore, inasmuch as this embodiment of the invention is designed to handle smaller sizes of crystals than those to be handled in the previously described tray. The tray for holding the smaller crystals comprises a top plate 60 and a bottom plate 61 held in spaced relation one from the other by posts 62, 63, 64 and 65, suitably attached to the top and bottom plates. Beneath each of the posts, that is, adjacent the corners of the bottom plate 61, a plurality of feet 66-66 are attached to the bottom plate for supporting it in spaced relation to any surface on which it is desired to place the tray. The top plate 60 has a handle 67 suitably attached or formed integrally with it and the plate is provided with a series of apertures 68 through which rinsing water and acid in the acid bath may pass to contact with crystals 69 held by the tray. In this embodiment of the invention, a plurality of shelves 70, all of exactly the same construction, are adapted to be placed between the top plate 60 and the bottom plate 61, and all of the shelves 70 have notches 71-71 cut in their ends to receive retainer pins 72-72, which may be passed through suitable apertures 73-73 in the top plate 60 and nested in pockets 74-74 in the bottom plate 61, thus to retain the stack of shelves 70 in the tray. In addition to the stack of shelves 70, a cover plate 75 is provided for the top shelf and this plate is provided with apertures 76 in alignment with the apertures 68 in the top plate

69. The purpose of this cover plate 75 will become apparent as the description progresses.

Each of the shelves 70 comprises a main body portion 80 extending from end to end of the shelf and there is provided an upstanding ledge 81 at each end of the shelf. Adjacent diametrically opposite corners of the shelves and extending upwardly from the ledges 81 are interlocking pins 82, which are adapted to enter sockets 83 (Fig. 8) extending upwardly from the lower surface of each of the shelves. In this manner, the shelves may be stacked and interlocked with each other prior to inserting them between the top plate 60 and bottom plate 61. Each shelf 70 is provided with a plurality of rows of apertures 84, as shown most clearly in Figs. 5, 6 and 7, the edges of which are milled adjacent the upper surface of the body portion 80 of the shelf to form sloping slots 85 diametrically opposed to each other. These slots are adapted to receive adjacent sides of a crystal so that the crystal will be supported with one of its corners extending directly downwardly at the center of the aperture 84, as shown most clearly in Fig. 5. The upper corner of the crystals 69 thus positioned on the shelves 70 will extend into the aperture 84 in alignment with it and formed in the next adjoining upper shelf 70 and in this manner the crystals will be prevented from dropping out of the shelves, although the shelves are tilted, together with the entire tray, during the course of dipping them in the acid bath or rinsing bath. Since the upper points of the crystals 69 are just below the plane of the upper surface of the ledges 81, the crystals 69 in the top shelf 70 would fall out of the shelf unless some device were provided for preventing this and, accordingly, the cover plate 75 is provided for the top shelf and this cover plate has a pair of apertures 86 adjacent diametrically opposed corners of it to receive the pins 82 on the topmost shelf 70 to be assembled in the tray. In order to permit the material of the various baths to contact practically all surfaces of the crystals 69, the bottom plate 61 has a cut-out 87 formed in its upper surface which makes it correspond generally to the construction of the shelves and the material of the acid or rinsing baths may freely enter the lower ends of the apertures 84 in the lowermost shelf due to the further provision of a plurality of apertures 88 in the bottom plate 61.

What is claimed is:

1. An article holding tray for supporting articles during their immersion in acid and rinsing baths comprising spaced, perforated top and bottom plates, means for rigidly interconnecting said plates one to the other, a plurality of article supporting shelves positionable between said top and bottom plates, said shelves having article receiving surfaces formed in them for receiving articles between them, and removable pins for locking said shelves in position between the top and bottom plates.

2. An article holding tray for supporting articles during their immersion in acid and rinsing baths comprising spaced, perforated top and bottom plates, means for rigidly interconnecting said plates one to the other, a plurality of article supporting shelves positionable between said top and bottom plates, said shelves having article receiving surfaces formed in them for receiving articles between them, and removable pins insertable through the top plate and into the bottom plate for locking said shelves in position between the top and bottom plates.

3. An article holding tray for supporting articles during their immersion in acid and rinsing baths comprising spaced, perforated top and bottom plates, means for rigidly interconnecting said plates one to the other, a plurality of perforated article supporting shelves positionable between said top and bottom plates, said shelves having article receiving surfaces formed in them for receiving articles between them, and removable pins for locking said shelves in position between the top and bottom plates, said bottom plate having ridges formed on its upper surface to cooperate with the bottom shelf to provide a passage for the bath materials to perforations in the bottom shelf.

4. An article holding tray for supporting articles during their immersion in acid and rinsing baths comprising spaced, perforated top and bottom plates, means for rigidly interconnecting said plates one to the other, a plurality of article supporting shelves positionable between said top and bottom plates, said shelves having article receiving surfaces formed in them for receiving articles between them, and removable pins for locking said shelves in position between the top and bottom plates, said shelves being notched at their ends to provide surfaces for engaging the pins when the tray is tilted, thereby to prevent the shelves from falling out of the tray.

5. An article holding tray for supporting articles during their immersion in acid and rinsing baths made completely of acid resistant material and comprising spaced, perforated top and bottom plates, means for rigidly interconnecting said plates one to the other, a plurality of article supporting shelves positionable between said top and bottom plates, said shelves having article receiving surfaces formed in them to receive articles between them, and removable pins for locking said shelves in position between the top and bottom plates.

6. An article holding tray for supporting articles during their immersion in acid and rinsing baths made completely of acid resistant material and comprising spaced, perforated top and bottom plates, means for rigidly interconnecting said plates one to the other, a plurality of article supporting shelves positionable between said top and bottom plates, said shelves having article receiving surfaces formed in them to receive articles between them, and removable pins extending through the top plate and into the bottom plate for locking said shelves in position between the top and bottom plates.

7. An article holding tray comprising a rectangular framework including a perforated top plate, a perforated bottom plate and spaced end members, shelf receiving grooves formed in the end members, perforated shelves having article receiving grooves formed therein insertable in the shelf-receiving grooves, removable side plates for holding articles on said shelves, and removable pins for locking the shelves in their shelf-receiving grooves.

8. An article holding tray comprising a rectangular framework including a perforated top plate, a perforated bottom plate and spaced end members, a handle extending transversely of and fixed to the top plate, shelf-receiving ways formed in the end members, perforated shelves having article receiving grooves formed in them insertable in the shelf-receiving ways, removable side plates having locking surfaces engageable with cooperating locking surfaces on the bottom plate, and removable pins for holding said side plates with their locking surfaces engaging the locking surfaces of the bottom plate.

9. An article holding tray for holding crystals during the etching and subsequent rinsing thereof comprising spaced top and bottom plates, means rigidly interconnecting the top and bottom plates, a series of interlocking nested shelves positionable between said top and bottom plates, crystal receiving surfaces formed in the upper surfaces of each of the nested shelves to position crystals between the shelves, and removable pins for locking the nested shelves in position between the top and bottom plates.

10. An article holding tray for holding crystals during the etching and subsequent rinsing thereof comprising spaced top and bottom plates, means rigidly interconnecting the top and bottom plates, a series of interlocking nested shelves positionable between said top and bottom plates, crystal receiving surfaces formed in the upper surfaces of each of the nested shelves to position crystals between the shelves, removable pins for locking the nested shelves in position between the top and bottom plates, said shelves having ledges at their ends for spacing the body portions thereof from adjoining shelves, pins extending from opposite ends of opposite ledges, sockets formed in the bottom of each shelf to receive the pins on the ledges, and a cover plate for the top shelf provided with apertures to receive the pins projecting from the ledges of the top shelf of a stack.

WILBUR L. HOFF.
